TEMPLLET AND SUPPORTING FRAME FOR LOCATING HINGE BUTT RECESSES IN DOORS AND DOORFRAMES

Elmer P. Sacrey, Syracuse, N. Y.; Caleb Candee Brown, Jr., executor of said Elmer P. Sacrey, deceased

Application January 23, 1952, Serial No. 267,839

3 Claims. (Cl. 33—197)

1

This invention relates to templet and supporting means for locating hinge butt recesses to be routed out in pieces of work, as in a door and the confronting edge of a door frame, and has for its object an instrument or tool comprising a templet and a supporting frame having coacting means operable to locate the templet along the edge of the door or door frame, and means for temporarily securing the frame and the templet to the work piece when properly adjusted, as to a door or door frame. More specifically, the templet has adjustable gauges to determine the length of the recesses, side gauges to determine the width of the recesses and the distance the recesses are to be inset from one lengthwise edge of the door or door frame, and side gauges coacting with the other lengthwise edge of the door and door frame in accordance with the thickness of the door and width of the door frame, and adjustable end gauges at opposite ends of the templet for locating the templet and recess a given distance from the top edge of the door or door frame.

The butts or leaves of hinges are of standard lengths and widths for standard sizes of hinges and doors and door frames. The recesses are always located to inset from one lengthwise edge of the door or door frame and to open through the opposite lengthwise edge. Doors usually have at least top and bottom hinges and also, in most instances, an intermediate hinge. The top and bottom hinges are located given distances from the top and bottom edges of the door in accordance with the height of the door. There is one templet for each supporting frame, and this templet is set or adjusted for all the hinges of the door and is shifted from one recess location to another and interlock with coacting locating means on the frame of the instrument or tool. The same setting is used when the instrument or tool is applied to the door frame.

Jobs for which this instrument or tool is adapted usually include a batch of doors of the same height, thickness, and hinge location, and door frames with the same setting of hinges as the doors, and the tool is adjustable for batches of doors of different sizes and thicknesses requiring another setting of gauges.

The specifications for the doors, hinges and hinge locations are supplied to the builder, or contractor. Surveys show that ninety-five percent of the doors specified are 6'6" and 6'8" in height. This instrument is built to locate the hinge butt recesses to be routed out in ninety-five percent of the doors and door frames. A

2

workman however can, when he becomes familiar with the instrument, readily set the instrument, within limits, to other various sizes of doors, or different specifications.

5 The routing out is done with a motor driven router having means for limiting the depth of the recess. In applying the instrument to the door, or the door frame, the workman always starts at the top end of the door and of the door frame. In applying the instrument to the door frame to locate the hinge butt recesses in the door frame, the workman reverses the supporting frame end for end.

10 The invention consists in the novel features and 15 in the combinations and constructions herein-after set forth and claimed.

In describing this invention, reference is had to the accompanying drawings in which like characters designate corresponding parts in all 20 the views.

Figure 1 is a fragmentary plan view of this instrument or tool, the position of the door being indicated in broken lines.

Figure 2 is a side elevation of parts seen in Figure 1.

Figure 3 is an enlarged sectional view on line 3—3, Figure 1.

Figure 4 is an enlarged sectional view on line 4—4, Figure 1.

30 Figures 5 and 6 are respectively a fragmentary plan and an inverted plan of one end of the templet showing the cam width gauges on the templet, the cam gauges on the lower side of the templet being shown in Figure 6.

35 Figure 7 is a fragmentary elevation of the extensions telescoping with the body of the supporting frame to locate the templet when shifted from one routing position to the other.

Figure 8 is a detail view of one of the extensions.

Figure 9 is a fragmentary plan view showing the instrument as applied to the door frame to locate the recesses to be routed in the door frame.

40 This templet and supporting frame for locating hinge butt recesses in doors and door frames comprises a supporting frame having a body and extensions adjustable lengthwise of the body, the body being provided with brackets extending laterally therefrom to overlie the edge of the work 50 to be recessed, and carrying means, as pins or nails, for temporarily securing the brackets to the work, and extensions at the ends of the body slidably telescoping thereinto, and a templet having a slot for exposing the surface of the work to be recessed, the templet having shiftable gauge pins

extending transversely of the slot and adjustable in a direction lengthwise of the slot to vary the length of the slot, side gauges at one lengthwise edge of the templet to engage the work and inset the templet with one side wall of the slot a given distance from said edge of the work; adjustable side stops; as cam gauges, on the under side of the templet and located to abut against the other lengthwise edge of the work in accordance with the thickness of the work, and end gauges at opposite ends of the templet adjustable endwise of the templet, the end gauges being located to hook over the top edge of the door to locate recesses to be routed out a given distance from the top edge of the door. The extensions of the frame and the templet have means for interlocking when the templet is shifted to be located a given distance from the top edge of the door. The body of the frame has similar means to interlock with the templet when a recess for a third intermediate hinge is used.

11 designates the supporting frame, and 12 the templet. The frame 11 is shown as provided with brackets 13 extending laterally from the body portion 11A thereof and when applied to the work, overlying the edge face of the door D and being provided with means as pins or nails 14, Figures 1 and 4, for being driven into the work to temporarily hold the frame to the work—that is, to the edge face of the door, or the confronting edge face of the door frame. These pins are shown as carried by plungers 15 slidably mounted in guides 16 on the brackets 13, the plungers 15 having heads 17 by means of which the plungers can be actuated to press the pins 14 into soft wood, or struck by a hammer to drive the pins into hard wood. Means, Figure 4, is provided for the withdrawal of the pins and as here shown, pry levers 18 are pivoted at 19 to the bracket 13 and engage under the heads 17 when the levers 18 are lifted about their pivots in order to pry up the plungers 15 and hence pull out the pins 14.

The body 11A of the frame 11 is here shown as tubular and provided with extensions or rods 21 which slidably telescope into opposite ends of the body and extend parallel to the door but offset therefrom when the instrument is applied to the door or door frame. Each extension has a scale as consecutive members 25, one of which is visible through a peep-hole 22, Figures 1 and 7, there being a peep-hole at each end of the body 11A. Each of these extensions has means as a pin 23 at a right angle thereto forming part of means for coupling or interlocking the templet thereto. Each of these extensions is, as shown in Figure 8, a split rod having transverse notches 24 therein located in accordance with the numbers of the scale 25. The notches 24 are for receiving a latch spring 26 anchored to each bracket 13 at 13A, Figure 4, and entering or snapping into the notches 24 through a slot 24A in the adjacent bracket 13 alined with one of the notches 24 when a selected number of the scale 25 is alined with the peep-hole 22.

The templet is provided with size gauges, as a pair of pins 30 extending transversely thereof and extending through holes 32 in upright side walls of the templet which is in the general form of a shallow channel in cross section, these holes being spaced apart in accordance with the length of the hinge butt, that is, the hinge butts from $2\frac{1}{2}$ to $5\frac{1}{2}$ inches long. The pins extend transversely of opposite ends of a slot 33 in the templet which, when the templet is in position on the

work, exposes the edge face of the work to be routed out. The pins 30 are located to adjust the length of the recess to be routed out. These pins 30 are here shown as slotted, or split, Figure 5, at one end in order that the split end may be compressed and frictionally held in the holes when the pins are set in position.

The templet is also provided with side gauges 35 pivoted at 36 to one of the lengthwise edges of the templet and shiftable to gauge or hook over one lengthwise edge of the door and thus cause the slot 33 to be inset at 37 a standard fixed distance from said lengthwise edge so that the recess to be routed will be also inset. The opposite edge of the recess opens through the opposite lengthwise edge of the door or work.

The templet is also provided with end gauges 38, there being an end gauge 38 at each end of the templet. Each end gauge comprises a spindle or stem which extends lengthwise of the templet and is provided with a flat, rabbeted, hook-shaped head 39 at its outer end for hooking over the top edge of the door when the instrument is set for routing out the recess toward the upper end of the door, and the other end stop being located to abut against the horizontal door frame member at the top of the door frame when the supporting frame 11 is inverted and applied to the door frame and the templet is shifted in position to locate the recess to be routed out toward the top end of the door frame. The hook-shaped outer end 39 is of such thickness as to provide a uniform clearance between the upper end of the door and the door frame. Each end gauge 38 is here shown as slidably mounted in a bearing 40 at each end of the templet and is also rotatably mounted. It is held in its adjusted position by a latch lever 41, Figures 1 and 3, mounted on each end of the templet and spring pressed to enter one of a series of transverse notches 42 in the stem of the end gauge 38. By giving the end gauge 38 a slight turn, the notches are shifted out of engagement with the latch lever, and the latch lever rides on the full periphery of the stem of the end gauge 38 so that the end gauge can be slid axially to any desired position or location and then turned back so that the latch lever 41 snaps into the alined notch. The position of each end gauge is determined by a scale on the end gauge 38 which designates the notches A, B, C, etc. These designations are considered in connection with a table, to be hereinafter explained, on the face of the templet for setting the end gauge in a selected position.

The bearings 40, Figures 1 and 3, are formed in inserts or castings 43 located in the channel formation of the templet 12 between the side walls of the channel formation and on the bottom wall of the formation beyond the ends of the slot 33 in the bottom wall of the templet 12. Each latch spring 41 is anchored at one end at 46 to the adjacent insert 43. To adjust each end gauge 38, the end gauge 38 is rotated in its bearing 40 so that the notches 42 ride out from under the latch spring 41. The end gauge is then pulled out or pushed in until the desired letter A, B, C, etc., is visible just beyond the end of the templet 12, and then the end gauge turned until a notch 42 is alined with the latch spring 41 so that the latch spring snaps into the notch. Each templet 12 is provided with means to temporarily secure the templet 12 to the door. As here shown, this means comprises pins or nails 47 secured to vertically movable slides or plungers 48 slidably in guides formed in a bracket 49 provided in each

insert 43. Each slide or plunger is formed with a head 50 with which a pry lever 50A coacts. The pins or nails 47, plunger 48 and its head 50, are similar to the pins or nails 14, plunger 15, and its head 17 and pry lever 18 for the securing means on the brackets 13 of the body 11A of the supporting frame 11.

The templet is also provided with calibrations designated generally 51, and with cam gauge levers 52 pivoted at 53 to the under side of the templet and held in their adjusted pivotal positions by nuts, as wing nuts 54A, exposed on the face of the templet, the wing nuts threading on the pivots 53 and serving to clamp the cam gauge lever 52 in its set or adjusted position. The calibrations are used to adjust the cam gauge levers to the width of the door, and the cam levers 52, when set, engage the face of the door through which the recess opens when routed out. The head 39 of one of the end gauges overhangs the top edge of the door. The head 39 of the other end gauge 38 abuts against the top member of the door frame when the supported frame is inverted end for end and also the templet inverted end for end, and the supporting frame and the templet applied to the door frame.

The brackets 13 of the body 11A of the frame are provided on the under sides thereof with cam lever gauges 52A pivoted at 53A to the bracket 13, one cam lever for each bracket, the cam lever gauges 52A coacting with the edge of the door frame to space the body 11A of the supporting frame a given distance from the edge of the door frame in accordance with the thickness of the door. The cam lever gauges 52A coact with calibrations on the under sides of the bracket 13, similar to the calibrations 51, Figure 6, and are clamped in their adjusted position by wing nuts 54A, Figure 1. The cam levers 52, 52A are used when the outer upright face of the door is to be located not flush or depressed relative to the edge face of the door frame.

The frame 11 and its extensions 21 and the templet 12 are provided with means which interlock and thus locate the templet when the end gauges 38 and other gauges are set, the means here shown being the pins 23 on the extensions 21 at a right angle to the extensions, and a similar pin 23A, Figures 1, 4, 7 and 9, on the tubular body 11A of the frame and laterally extending slots 55 in ears 56 extending laterally from one of the side edges of the templet midway between the ends thereof. The pin 23A is located midway between the ends of the tubular body 11A. Thus, with the size pins 30 set in a desired position and the end gauges 38 and also the gauges 35 set, the extensions 21 can be set so that the pins 23 thereof enter the slots 55. The recesses can then be routed out one by one, the templet shifted from one end of the work to the other end, as indicated in dotted lines, Figure 1, and another recess routed out and then the templet can be shifted so that it interlocks with the pin 23A of the body 11A, and the central recess routed out. Of course, the templet may be shifted to rout out the recesses in any other order.

In locating the hinge butt recesses to be routed out in the door frame, the assembled instrument is reversed, Figure 9, or inverted end for end, and the templet located at the upper end of the inverted supporting frame 11 and applied and temporarily secured to the door frame F, or jamb, with the same setting of the gauges as when the instrument was applied to the door. If the last recess of the door routed out was the recess for

the lower hinge, the templet 12 will be at the top end of the door frame, or jamb, when the instrument is inverted. If not, the templet is located at the upper end of the extension 21 of the supporting frame 11. The head 39 of the now uppermost end gauge 38 will abut against the top horizontal member F of the door frame. The instrument is now pressed flat against the door frame and temporarily secured to the door frame by driving in the pins or nails 42 of the templet, and then the pins or nails 14 of the supporting frame. As the instrument is pressed flat on the door frame, the end gauges 38 automatically rock about the axis of its stem as the angular head 39 thereof presses against the door frame. Likewise the templet gauges 35 rock about their axes and the corresponding gauges 35A at the ends of the brackets 13 are pressed out of operating position.

If the door stop S is not installed when the hinge butt recesses are being located, the cam gauges 52 of the templet and the corresponding gauges 52A on the lower sides of the brackets 13 of the body 11A of the supporting frame are set in accordance with the thickness of the door. If the door stop is installed, it is not necessary to use the cam gauges to determine the width of the recess from the inset wall thereof to where it opens through the opposite side edge of the door jamb. Usually the door is hung so that when closed, the inner face of the closed door is not flush with, but is depressed slightly below, the inner edge face of the door jamb. The cam gauges 52, 52A, are set to effect this depression.

To guide the workman in setting the instrument, a table T is provided on the bottom of the channel formation of the templet 12, Figure 5, the table applicable for 6' 8" doors being here partly illustrated.

In operation, the gauge pins 30 are located in a pair of holes 32 to space them far enough apart to gauge the slot 33 as to its length in accordance with the length of the recess to be cut for the hinge butt. The end gauges 38 are then adjusted as, for instance, for hinges to be spaced 5½ inches from the top and the bottom hinge 9½ inches from the bottom so that the letter B of the scale of the end gauge 38 is visible just beyond the end surface of the template through which the gauge 38 slides in accordance with the numbers in the first and second rows of the table T. The extensions 21 are adjusted so that the numbers 8-8 appear in the peepholes 22 of the body 11A of the supporting frame, as indicated in the third column of the table T. The fourth column indicates the letters, as the letters B-B to which the end gauges 38 are to be set. The gauges of the templet are so set when there are three hinges to be applied to the door and the door frame and this setting locates the intermediate hinge half way between the top and bottom hinges. However, in case two hinges—that is, the top and bottom hinges only are to be installed, the setting is the same except that the end gauges are set in position to locate the top and bottom hinges at the specified distances from the top and bottom edges of the door. As the distance from the bottom edge of the door from the bottom hinge may be different from when three hinges are to be installed, the extension 21, toward the bottom end of the door, is not necessarily set with the same number in the peephole 22 as the top extension 21, but is set in a position that can readily be computed by the workman. However, both the end gauges 38 on the template are set in accordance with

the distance indicated on the table T by the letters A—A, B—B, C—C, etc., in line with the numbers in the first column of the chart indicating the distance the top recess is to be from the top edge of the door indicated by the letters. The table T thus acts as a sort of automatic computator for the setting of the gauges of the templet and the extensions of the supporting frame eliminating entirely the need for a ruler.

The features of this templet and supporting frame which characterizes the invention are the positive locking means, as the latch lever 26 on the body 11A of the frame, or the laterally extending bracket arms 13 thereof, coacting with the notches 24 in the extensions 21 to positively lock the extensions 21 in their selected adjusted position when the desired numbers are visible in the peep holes 22, and also the positive locking means, as the latch levers 41, Figures 1 and 3, coacting with the notches 42 in the end gauges 38 of the templet 12, all so that the adjustments, when made, can not be upset by rough handling and dropping of the supporting frame, or the templet, when the adjustments are made for other doors of a batch of like doors and door frames.

Another characteristic feature is the locating pins 23 and 23A interlocking with the slot 53 in the lateral lug 56 of the templet to locate the templet in position for routing out the top, intermediate and bottom recesses, the pin 23A on the body 11A being located midway between the ends of the tubular body 11A, or midway between the peep holes 22.

With the adjustments made, the templet is located so that one of the end gauges hooks over the top of the door to locate the upper hinge butt recess when the supporting frame and templet are applied to the door and the other recesses are automatically located when the adjustments are made in accordance with the table T on the face of the templet, and also when applied to the door frame. When the supporting frame is applied to the door frame, the supporting frame is inverted end for end, and also the templet is inverted end for end relative to the supporting frame and located at the upper edge of the door frame with the other end gauge abutting against the horizontal member at the top of the door frame. The adjustments automatically locate the positions of the intermediate and bottom hinge butt recesses when the templet is shifted from its position at the top of the door to its intermediate and bottom positions along the supporting frame and the extensions. The notches 24 in the extensions 21 are actually spaced $\frac{1}{2}$ " apart to facilitate the setting of the extensions 21 in accordance with the table T.

What I claim is:

1. A templet and supporting frame for locating hinge butt recesses to be routed out in work, as doors and door frames, comprising a supporting frame having a tubular body and means extending laterally therefrom for attachment to the work; adjustable extensions telescoping into opposite ends of the body; the templet having a lengthwise slot intermediate its ends for exposing the surface to be recessed; gauge means on the templet to locate the templet on the work to be recessed including like end gauges at opposite ends of the templet and extending and adjustable lengthwise beyond said ends, one end

gauge being located to hook over the top edge of the door when the templet is applied to the door and the other end gauge being located to abut against the horizontal top rail of the door frame when the supporting frame is inverted end for end and applied to the door frame and the templet is also inverted relative to the supporting frame end for end, means on the templet and the supporting frame to temporarily secure them to the door and door frame alternately, the templet being shiftable relative to the work and supporting frame into position to locate the hinge butt recesses; coacting parts on the templet, body of the supporting frame and extensions to locate the templet in its shifted positions comprising fixed pins projecting radially from the body and each extension and a lug projecting laterally from one side of the templet and having a slot for selectively receiving one of the pins; scales on the extensions and the templet for indicating the selected adjusted positions thereof; releasable locking means on the supporting frame coacting with the extensions to positively lock the extensions in their selected adjusted positions; and releasable locking means on the templet and coacting with the end gauges to positively lock the end gauges in their adjusted positions.

2. A templet for locating hinge butt recesses to be routed out in work, as doors and door frames, the templet being channel shaped in cross section and formed with a lengthwise slot intermediate of its ends and located to expose the surface of the work to be recessed, a pair of gauge pins extending transversely of the channel formation and the slot and adjustable to different positions relative to the slot to adjust the length of the recess to be routed out, releasable plunger means on the templet to temporarily secure it to the work, a pair of end gauges on the templet each having a plurality of notches therein, and a pair of spring biased elements on said templet respectively engageable with the notches in the end gauges to permit longitudinal adjustment thereof.

3. In a device for locating hinge butt recesses to be routed out in work, as doors and door frames; a supporting frame comprising a tubular body, means extending laterally from said body to releasably secure it to the work, gauge means on said laterally extending means to control the distance said body is spaced from said work, adjustable extensions telescoping into opposite ends of said body, and a radially extending pin on each of said extensions and on said body; and a templet including a lengthwise aperture intermediate its ends for exposing the work surface to be recessed; and a lug projecting from one side of said templet having a pin receiving slot therein to permit said templet to be successively engaged with each of said pins thereby successively positioning the templet opposite the work surfaces to be recessed.

ELMER P. SACREY.
